UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed December 19, 1924, Serial No. 757,032. Renewed April 13, 1928.

My invention relates to mining machines.

An object of my invention is to provide an improved mining machine. Another object of my invention is to provide a mining machine of improved and very compact construction especially adapted to use in mines having narrow or low veins. Still another object of my invention is to provide an improved mining machine of the self-propelled, 10 flexibly fed type having improved simple and compact feeding means therefor whereby the feeding of the machine is greatly facilitated. Still another object of my invention is to provide an improved mining machine of the invertible type adapted to operate selectively as an overcutter or an undercutter. A still further object of my invention is to provide an improved mining machine of the flexibly fed type having improved driving and guiding means for the flexible feeding member. Still another object of my invention is to provide an improved flexibly fed mining machine of the convertible chain or wire rope type having 20 improved and simplified means whereby the parts may be interchanged with facility and improved means for guiding the feed chain or feed rope. Another object of my invention is to provide an improved flexibly fed mining machine having improved feed transmission mechanism whereby either a reversible or unidirectional driving motor may be utilized. These and other objects and advantages of my invention will, however, 30 hereinafter more fully appear.

In the accompanying drawings I have shown for purposes of illustration four embodiments which my invention may assume in practice.

40 In these drawings,—

Fig. 1 is a plan view of a longwall mining machine constructed in accordance with one illustrative embodiment of my invention.

Fig. 2 is a side elevation of a portion of 45 the front or feeding end of the machine.

Fig. 3 is an end elevation of the feeding end of the machine shown in Fig. 1.

50 Fig. 4 is an enlarged, vertical, longitudinally extending, developed sectional view through the improved feeding mechanism, the view being taken substantially on line 4-4 of Fig. 1.

Fig. 5 is a vertical transverse sectional view through the planetary reduction gear-

ing, the view being taken substantially on 55 line 5-5 of Fig. 4.

Figs. 6 and 7 are detail sectional views of a slightly modified form of the feeding mechanism illustrated in Fig. 4, Fig. 7 being taken substantially on line 7-7 of Fig. 6. 60

Fig. 8 is an end elevational view of the feeding end of the machine, the view being a modified form of that illustrated in Fig. 3 adapted to use with a chain feeding member.

Fig. 9 is a partial side elevation of Fig. 8 65 of the machine illustrating my improved chain guiding arrangement.

Fig. 10 is an end elevational view of a further modified form of the feeding end of the machine shown in Fig. 3 especially adapted 70 to use with a wire feed rope and a unidirectional driving motor.

Fig. 11 is a side elevation of the feeding and guiding arrangement shown in Fig. 10.

Fig. 12 is a further modified end elevational view of the feeding end of the machine illustrating the chain form of feed utilized with a unidirectional driving motor. 75

Figs. 13, 14 and 15 are diagrammatic views illustrating the operation of the machine during cutting. 80

In the illustrative construction shown in Figs. 1 to 5, 13, 14 and 15, I have shown my invention incorporated in a mining machine of the same general type as described in my copending applications, Ser. No. 619,839, filed Feb. 19, 1923; Ser. No. 705,089, filed April 8, 1924; and Ser. No. 719,691 filed June 12, 1924, and which is herein of the self-propelled flexibly fed longwall type adapted to 85 slide on its bottom on the mine bottom and having an invertible elongated machine frame 1 presenting parallel plane surfaces 2 and 3 upon which the machine is selectively adapted to slide during operation, that is, 90 when the machine is being used as an undercutter or an overcutter. The machine frame 1 carries at one end a horizontal cutter bar 4 about the outer edges of which the usual endless cutter bit carrying cutter chain 5 is 95 adapted to be circulated, the bar being pivoted on a vertical axis, as at 6, on the rear end of the frame. The mining machine is herein also adapted to be moved longitudinally 100 relative to the face of the coal relative to a flexible feeding means of any suitable form, herein including a flexible feeding member or wire rope 7, adapted to cooperate with a

85

95

100

105

feed operating member or winding drum 8 rotatable on a horizontal longitudinally extending axis on the front end of the frame 1. As illustrated, the machine frame 1 further 5 comprises a motor section 9, a cutting mechanism carrying section 10, a feed transmission carrying section 11, and a drum support and guiding section 12 and these frame sections are rigidly secured together in any 10 suitable manner, the motor section 9 being interposed between the sections 10 and 11, in the usual manner.

In my improved construction it will be observed that the motor casing 9 houses an electric driving motor 13 (see Fig. 1), herein of the usual reversible type, provided with a horizontally disposed, longitudinally extending armature shaft 13'. The winding drum 8 is herein arranged coaxially with the motor armature shaft. The cutter chain 5 is driven through suitable transmission mechanism, not shown, from the rear end of the armature shaft, but as this transmission means does not enter into my present invention further description of the cutting mechanism is deemed unnecessary, with the exception that the cutter bar 4 is adapted to be swung about its pivot 6 and locked to the machine frame, in the usual manner, in a plurality of positions. In my improved feeding mechanism it will be observed that the forward end of the armature shaft 13' has secured thereto, as by a key and nut and washer connection 14, a driving pinion 15 which is adapted to drive the feed drum 8 through transmission mechanism, to be hereinafter described, selectively at a slow or a fast speed in the same direction in a manner substantially similar to that described in my copending application Ser. No. 619,839 mentioned above. In specifically considering the fast speed mechanism it will be noted that the pinion 15 meshes with a spur gear 16 keyed to a horizontal longitudinally disposed shaft 17 journaled in suitable bearings 18 carried by a ring section 19 receivable in a corresponding longitudinally disposed and centrally located bore 20 extending the length of the frame section 11. This ring section 19 is adapted to be inserted within or removed longitudinally from the rear end of the frame section 11 and has herein, preferably, a cut away portion 21 in which the gear 16 is disposed and a web or hub portion 22, by which the bearings 18 and a bearing 23 are carried, the latter being the bearing within which one end of a longitudinally disposed main feed driving shaft 24, is journaled. As shown, the shaft 17 and the gear 16 are suitably located relative to the bearings 18 by suitable bearing washers and the shaft at one end projecting from one bearing and carrying a pinion 25 thereon which, in turn meshes with a larger internal gear 26, the pinion and bearing being held together in assembled re-

lation by a suitable bolt connection 27. The hub 28 of the gear 26 is herein also journaled on a suitable bearing sleeve 29 on a sleeve clutch member 30 keyed, as at 31, to the rear end of the shaft 24. Moreover, it will be noted that the member 30 carries a series of friction disks 32 surrounding the member 30 and disposed within the sleeve on the internal gear 26, these disks cooperating with a corresponding series of disks 33 carried by the sleeve on the internal gear. As shown, the sleeve on the internal gear is also provided with a plurality of radially located, longitudinally extending slots 34 receiving radial fingers 35 on an interlocking member 36 keyed to a pinion 37 which is in turn freely rotatable on the shaft 24. Between these fingers 35 are friction clutch operating fingers 38 carried by a cylindrical plane member 39 disposed coaxially with the hub of the gear 26. These fingers 38 extend longitudinally in contact with one set of the friction disks 32, 33. As shown, the opposite end of the shaft 24 is also journaled in suitable bearings 40 carried in the hub 41 of a ring section 42, similar to the section 19, and a pinion 43, similar to the pinion 37, secured to the shaft at a point adjacent the bearing 40. This pinion, in turn, meshes with a plurality of planetary gears 44 journalled in bearings 45 carried by longitudinally extending studs 46 formed on radial arms of a spider member 47, in turn suitably secured to a horizontal longitudinally extending shaft 48. This shaft is disposed coaxially with the shaft 24 and in front thereof, and is journaled within suitable longitudinally spaced roller bearings 49 and 50, the former being carried by the frame section 12 while the latter is disposed within a recess 51 formed within a cylindrical member 52 likewise disposed in the bore 20 and held in non-rotatable relation with respect thereto by means of a key 53. The member 52 has formed thereon a large internal gear 54 with which the planetary gears 44 are meshed. The forward end of the shaft 48 has secured thereto, as by a key and split ring connection 55, a clutch member 56 provided with external clutch teeth which are adapted to be connected by means of a longitudinally reciprocable internal gear clutch member 57 in driving relation with an external gear clutch member 58 journaled on the periphery of the member 56 and which is keyed, as at 59, to the winding drum 8. It will herein be noted that by manipulating the clutch member 57 the winding drum 8 may be driven or remain idle with respect to the drive shaft 48 at the will of the operator, thus facilitating the rewinding of the cable on the drum. Thus it will be noted that when the clutch 57 and the clutch 32, 33 are connected, the rotation of the armature shaft 13' will be transmitted to the pinion 15, the gear 16, the pinion 25, internal gear 26, the clutch 32, 33, the clutch 125

member 30, the shaft 24, the pinion 43, planetary gears 44 which react on the stationary internal gear 54, the spider member 47, the shaft 48, and to the winding drum 8 to rotate the latter at a predetermined high or fast speed especially adapted to use in hauling the machine about the mine. It will further be evident that by slipping the clutch elements 32, 33 the speed of feed may be lowered at will.

Referring specifically to the slow or cutting feed, it will be noted that when the clutch operating member 38 is in inoperative position and the clutch 32, 33 is released, power will still be transmitted to the interlocking member 35 through the pinion 37 which is freely rotatable on the shaft 24. This pinion in turn meshes with a spur gear 60 carried on a shaft 61 similar to the shaft 17 and journaled within bearings 62 within a ring section 63 similar to the ring sections 19 and 42 and likewise carried in the bore 20 and spaced from the ring section 19 by means of an intermediate spacing section 64 by which suitable shipper mechanism, not shown, for the clutch operating member 38 is carried. As illustrated, the hub of the ring section 63 carries a roller bearing 63' for the shaft 24 and it will be noted that the shaft 61 carries a pinion 65 meshing with a larger internal gear 66 keyed, as at 67, to the sleeve of a pinion 68 freely rotatable on the shaft 24. The pinion 68 meshes with a spur gear 69 keyed to the shaft 70, similar to the shaft 61 and disposed coaxially therewith. The shaft 70 is provided with a forwardly projecting end to which a pinion 71 is suitably secured and which pinion meshes with a larger internal gear 72. The internal gear 72 also houses a friction clutch substantially similar to the friction clutch heretofore described in connection with clutch disks 32, 33 and this clutch includes clutch disks 73 and 74 certain of which are carried by the sleeve formed on the gear 72 while others are carried by a clutch member 75 keyed, as at 76, to the driving shaft 24. A cylindrical sleeve member 77 is disposed between the bearing 40 for the forward end of the shaft 24 and the clutch member 75 and this sleeve has keyed thereto a member 78, similar to the clutch member 36, but which in this case has no interlocking function and is only a disk retaining member. A plane clutch operating member 79, similar to the member 39, surrounds the hub of the member 78 and is likewise adapted to be engaged by any suitable shipper operating mechanism, not shown. A ring section 80, similar to the sections 19, 42, and 63, is disposed between the sections 42 and 63, these sections being non-rotatably secured in the bore 20 by means of suitable keys 81. As a result of this mechanism above described, although the clutch 32, 33 is disconnected, rotation will constantly be transmitted through the pinion 37,

gear 60, pinion 65, internal gear 66, pinion 68, spur gear 69, pinion 71, internal gear 72, clutch 73, 74, clutch member 75, shaft 24, the pinion 43, the planetary gears 44, spider 47, the shaft 48, and the clutch members 56 and 58, so that when the clutch 73, 74 and the clutch member 57 are connected the winding drum 8 will be rotated at a slow or cutting speed in the same direction as the fast speed, previously described. Here it will also be evident that by slipping the friction 73, 74 this speed may be reduced when desired.

It will herein be noted that the cable 7 wound upon the drum 8 is adapted to be selectively extended longitudinally along the side of the machine frame 1, as indicated in Fig. 1, and connected in any suitable manner to the cutter bar 4, to swing the bar about its pivot, or extended forwardly from the machine frame 1 and attached to a fixed extraneous abutment or roof jack to feed the machine relative to the working face of the coal. Improved guiding means are provided for guiding the cable when extended in such manner. Disposed on parallel vertically disposed, longitudinally spaced studs secured at each side of the frame section 12 and equally spaced from each side of the winding drum 8 are guiding rolls 82, 83, 84, and 85 which are rotatable in a horizontal plane disposed substantially tangent with the winding surface of the drum 8. The guide rolls 82 and 84 are so spaced from the guide rolls 83 and 85 that the cable 7 may be freely dropped in between the rolls, consequently eliminating any threading of the cable during rearrangement thereof and thus facilitating the operation of the machine.

In the operation of my improved mining machine described above it will be observed that when the machine is disposed as shown in Fig. 13 it is possible for the cable 7 to be so arranged relative to the guiding rolls and the drum to swing the bar in the desired direction, as from the dotted line position shown in Fig. 13 to the full line position, and then rearranged to move the machine bodily longitudinally along the face, the cable having its free end connected to a roof jack A. More specifically it will be noted that when the bar is in the dotted line position it is unlocked from the machine frame and the cable 7 extended from the bottom of the drum 8 laterally of the machine frame and around the guide roll 83 and then rearwardly longitudinally along the side of the machine frame and suitably attached to the bar. Thus a pull upon the cable at a slow feeding speed produced by a suitable operation of the clutch 73, 74 causes the bar to be swung or sumped into the coal to a point substantially at right angles to the machine frame and is then again suitably locked in position. After the bar has been thus adjusted, the chain is disconnected therefrom and directed around and rear-

wardly of the guide roll 82 to the jack A whereupon by similarly operating the clutch 73, 74 the machine will move along the face at a slow or cutting speed. If, on the other hand, it is desired to have the machine cut in the opposite direction relative to the same coal face, it will be evident that by rearranging the parts as shown in Fig. 14 the same results may be obtained, the cable 7 being removed from the drum and rewound upon the drum in an opposite manner and extended transversely of the machine frame around the guide roll 85 and similarly connected to the bar. The driving motor 13 is then reversed and the cutter bits reversed in their respective links and the bar then swung or sumped into the coal. The cable is then disconnected from the cutter bar and extended around the guide roll 84 and longitudinally along the coal face to the jack A and the machine will move along the face at a slow or cutting speed. Furthermore it will be evident that if it is desired to cut in an oppositely located face the same results may be obtained by arranging the parts reversely as shown in Fig. 15, the cable 7 being selectively guided by the guide rolls 85 and 84, respectively, during the bar swinging and feeding operations.

It will herein be observed that in the form of my invention shown in Figs. 6 to 9 I have shown a mining machine of the same general type as heretofore herein described with the exception that the drum 8 is removed and replaced by a feed chain sprocket 86 and the guide rolls 82, 83, 84 and 85 are replaced by suitable chain guide sprockets 87 and a feed chain 88 is then utilized in place of the wire rope 7. Furthermore, the slow feed has inserted therein between the gears 68 and 69^a, as shown in Figs. 6 and 7, an intermediate spur gear 89 disposed on a horizontal longitudinally extending shaft 90 parallel with the axis of the shafts 85 and 70 and the slow speed is thereby rotated in an opposite direction from the fast speed. The feed chain sprocket 86 and the chain guide sprockets 87 are so arranged that threading of the feed chain 88 relative thereto is unnecessary, the chain being merely thrown over the feed sprocket and in between and around the guide sprockets, consequently facilitating the operation of the machine. The operation of this form of my invention is substantially the same as shown in Figs. 13 to 15 with the exception that the feed sprocket 86 may be rotated at a slow speed in one direction to draw in one portion of the feed chain or may be rotated at a fast speed in the opposite direction to draw in the other portion of the feed chain, the feed chain being similarly guided by the sprockets 87 in substantially the same manner as shown in Figs. 13 to 15 relative to the feed sprocket 86. If desired a chain stripper may be utilized for stripping the

chain 88 from the feed sprocket 86 or, if the use of a chain stripper is not desired, the receding slack chain may be manually pulled from the sprocket as the machine is fed along the coal face. It will further be noted that the motor 13 may be reversed when desired.

In the form of my invention shown in Figs. 10 and 11 a feeding mechanism is utilized substantially similar to that shown in Figs. 4 and 5 with the exception that a unidirectional driving motor in place of the reversible motor 13 is used, the motor being of the type described in my copending application, Ser. No. 619,839 mentioned above, and that an additional set of guiding rolls 91 is utilized similar to and disposed coaxially with the guiding rolls 82, 83, 84, and 85 and disposed in a similar spaced relation with respect to the drum at the opposite side of the horizontal center line of the machine. The operation of this form of my invention is substantially similar to that of the operation of the form shown in Figs. 1 to 5 with the exception that when the machine is cutting in opposite directions the drum is not reversed and the cable 7 is extended to the opposite sides of the machine and is guided by either set of the upper and lower diagonally disposed guide rolls, the cable being shown in full and dotted lines in that figure. It will further be observed that the cable may be unwound from the drum and rewound in a reverse manner, the other diagonally disposed set of upper and lower guide rolls guiding the cable at this time.

It will herein be observed that the form of my invention shown in Fig. 12 is substantially the same as that shown in Figs. 8 and 9 with the exception that a unidirectional driving motor is used, heretofore brought out above in connection with Figs. 10 and 11, and another set of chain guide sprockets 92 are disposed coaxially with the chain sprockets 87 and in a similar spaced relation with respect to the feed sprocket at the opposite side of the horizontal center line of the machine. The operation of this form of my invention is substantially similar to that shown in Figs. 8 and 9 with the exception that the feed chain sprocket rotates in a single direction during cutting in opposite directions and the feed chain 88 is extended selectively along the opposite sides of the machine frame and guided relative to the chain sprocket 86 by the desired set of chain guiding sprockets 89, 92 as indicated by full and dotted lines.

It will further be observed that the mining machine described above may be mounted on a suitable transport truck described in my copending application Ser. No. 723,953, filed July 3, 1924. When the machine is positioned on such a transport truck with the feed operating member disposed in alignment with and adjacent the truck driving member thereof, herein the member 93, indicated by dotted lines in Fig. 4 which is generally similar to

the driving member 31 in the above mentioned copending application, the clutch element 57 may be thrown over into mesh with the member 93, connecting the latter and the member 56 in driving relation and simultaneously disconnecting the drive for the member 58 secured to the feed operating member. The transport truck may then be driven at a fast or slow speed and at suitable variants 5 thereof under the control of the feed clutches of the mining machine while the feed operating member remains idle. It will also be noted that if desired, when the machine is positioned on the truck in such manner, the 15 clutch member 53 may be thrown over in mesh with the member 58 and disconnected from the member 93, thus enabling the feed operating member to operate while the truck driving member is inoperative.

20 While I have in this application specifically described four embodiments which my invention may assume in practice, it will be understood that these forms of the same are shown for purposes of illustration and that 25 the invention may be modified and embodied in various other forms without departing from its spirit or the scope of the appended claims.

What I claim as new and desire to secure by 30 Letters Patent is:

1. In a mining machine, a feed operating member rotatable on an axis extending longitudinally of the machine frame and adapted to cooperate with flexible feeding means, and plural speed transmission means coaxial therewith including planetary gearing, all the gears of said transmission means being rotatable on axes parallel to a line parallel with the axis of said feed operating member.

2. In a mining machine, a feed operating member rotatable on an axis extending longitudinally of the machine frame and adapted to cooperate with flexible feeding means, and transmission means driving said member including plural speed gearing and planetary reduction gearing both disposed coaxially with said member, all the gears of said transmission means being rotatable on axes parallel to a line parallel with the axis of said feed operating member.

3. In a mining machine, a feed operating member rotatable on an axis extending longitudinally of the machine frame and adapted to cooperate with flexible feeding means, and transmission means driving said member including plural speed friction controlled gearing and planetary gearing both disposed coaxially with said member, all the gears of said transmission means being rotatable on axes parallel to a line parallel with the axis of said feed operating member.

4. In a mining machine, a feed operating member rotatable on an axis extending longitudinally of the machine frame and adapted

to cooperate with flexible feeding means, and plural speed transmission means disposed coaxially with said member driving the latter including a controlling clutch and planetary reduction gearing, all the gears of said transmission means being rotatable on axes parallel to a line parallel with the axis of said feed operating member.

5. In a mining machine, a feed operating member rotatable on an axis extending longitudinally of the machine frame and adapted to cooperate with flexible feeding means, and plural speed transmission means disposed coaxially with said member driving the latter including a plurality of speed controlling clutches and planetary reduction gearing, all the gears of said transmission means being rotatable on axes parallel to a line parallel with the axis of said feed operating member.

6. In a mining machine, a motor, a feed operating member rotatable on a shaft extending longitudinally of the machine frame and adapted to cooperate with flexible feeding means, and transmission means between said motor and shaft for driving said member at variable speeds including a plurality of speed controlling clutches arranged coaxially therewith and planetary reduction gearing, all the gears of said transmission means being rotatable on axes parallel to a line parallel with the axis of said feed operating member.

7. In a mining machine, cutting mechanism, a driving motor therefor, a feed operating member rotatable on a longitudinal axis at the end of said machine opposite from said cutting mechanism and adapted to cooperate with flexible feeding means, and transmission means between said member and the adjacent end of said motor including planetary reduction gearing arranged coaxially therewith, all the gears of said transmission means being rotatable on axes parallel to a line parallel with the axis of said feed operating member.

8. In a mining machine, a motor, cutting mechanism, a feed operating member rotatable on a longitudinal axis at the end of the machine opposite from said cutting mechanism and adapted to cooperate with flexible feeding means, and variable speed transmission means between said motor and said member disposed coaxially with the latter including a plurality of speed controlling clutches and planetary reduction gearing, all the gears of said transmission means being rotatable on axes parallel to a line parallel with the axis of said feed operating member.

9. In a mining machine, a motor having a rotor, a feed operating member rotatable on an axis extending in the same direction as the axis of said rotor and adapted to cooperate with flexible feeding means, and transmission means arranged coaxially with said member for driving the latter at fast and slow speeds including planetary reduction gear-

- ing, all the gears of said transmission means being rotatable on axes parallel to a line parallel with the axis of said feed operating member.
- 5 10. In a mining machine, a motor, a feed operating member adapted to cooperate with flexible feeding means, and transmission means arranged coaxially with said member for driving the latter at fast and slow speeds including planetary reduction gearing, and a plurality of friction speed controlling clutches also coaxial with said member, all the gears of said transmission means being rotatable on axes parallel to a line parallel 70
10 with the axis of said feed operating member.
11. In a mining machine, a motor, a feed operating member disposed on a horizontal longitudinally extending axis driven thereby and adapted to cooperate with flexible feeding means, and transmission means between said motor and said member including variable speed mechanism and planetary gearing and a shaft driven by the latter, all the gears of said transmission means being rotatable on axes parallel to a line parallel with the axis of said feed operating member, and means disposed coaxially with said member for connecting or disconnecting the latter with respect to said shaft.
- 20 12. In a mining machine, a feed operating member having a horizontally disposed axis extending longitudinally of the machine frame and adapted to cooperate with flexible feeding means, and transmission means disposed coaxially with said member for driving the latter including plural speed gearing and planetary reduction gearing between said first mentioned gearing and said member, all the gears of said transmission means being 80
25 rotatable on axes parallel to a line parallel with the axis of said feed operating member.
- 30 13. In a mining machine, a motor having a rotor, a feed operating member disposed parallel with a line parallel with the axis of said rotor and adapted to cooperate with flexible feeding means, and plural speed transmission means between said motor and said member and disposed coaxially with the latter including variable speed mechanism 90
35 and planetary reduction gearing, all the gears of said transmission means being rotatable on axes parallel to a line parallel with the axis of said feed operating member.
- 40 14. In a mining machine, a motor having a rotor, a feed operating member disposed parallel with a line parallel with the axis of said rotor and adapted to cooperate with flexible feeding means, and plural speed transmission means disposed coaxially with said mem- 100
45 ber and between said motor and said member for driving the latter at variable speeds including planetary reduction gearing, all the gears of said transmission means being rotatable on axes parallel to a line parallel with the axis of said feed operating member.
- 50 15. In a mining machine, a motor, cutting mechanism, a feed operating member disposed on a horizontal longitudinally extending axis at the end of said machine opposite from said mechanism and adapted to cooperate with flexible feeding means, and transmission means between said motor and said member for driving the latter at variable speeds including planetary reduction gearing, all the gears of said transmission means being 75
55 rotatable on axes parallel to a line parallel with the axis of said feed operating member.
16. In a mining machine, cutting mechanism, a motor having a rotor, a feed operating member disposed parallel with a line parallel with the axis of said rotor at the end of said machine opposite from said mechanism and adapted to cooperate with flexible feeding means, and transmission means for driving said member from said motor including planetary reduction gearing disposed coaxially with said member, all the gears of said transmission means being rotatable on axes parallel to a line parallel with the axis of said feed operating member.
- 60 17. In a mining machine, cutting mechanism, a motor having a rotor, a feed operating member disposed on an axis parallel to a line parallel with said rotor at the end of said machine opposite from said mechanism and adapted to cooperate with flexible feeding means, and transmission means between said motor and said member including planetary reduction gearing, all the gears of said transmission means being rotatable on axes parallel to a line parallel with the axis of said feed operating member.
- 65 18. In a mining machine, a machine frame having a bore, a motor having a rotor, a feed operating member adapted to cooperate with flexible feeding means, and transmission means between said motor and said member housed in a bore in the machine frame disposed parallel with a line parallel with the axis of said rotor and including planetary reduction gearing disposed in said bore.
- 70 19. In a mining machine, a machine frame having a bore, a motor having a rotor, a feed operating member adapted to cooperate with flexible feeding means, transmission means between said motor and said member housed in a bore in the machine frame disposed parallel with a line parallel with the axis of said rotor and including variable speed mechanism and planetary reduction gearing both disposed in said bore.
- 75 20. In a mining machine, a motor, a feed operating member adapted to cooperate with flexible feeding means and rotatable on an axis extending longitudinally of the machine, plural speed transmission means between said motor and said member coaxial with the latter, all the gears of said transmission means being rotatable on axes parallel to a line parallel with the axis of said feed operating member.

allel with the axis of said feed operating member, and means including a sliding clutch for connecting or disconnecting said member with respect to the terminal element of said 5 transmission means.

21. In a mining machine, a motor, a feed operating member adapted to cooperate with flexible feeding means and rotatable on an axis extending longitudinally of the machine, 10 plural speed transmission means between said motor and said member coaxial with the latter, all the gears of said transmission means being rotatable on axes parallel to a line parallel with the axis of said feed operating 15 member and means including a sliding clutch disposed coaxially with said member for connecting or disconnecting said member with respect to the terminal element of said transmission means.

22. In a mining machine, a motor, a feed operating member adapted to cooperate with flexible feeding means and rotatable on an axis extending longitudinally of the machine, plural speed transmission means between 25 said motor and said member coaxial with the latter, all the gears of said transmission means being rotatable on axes parallel to a line parallel with the axis of said feed operating member, and means including a sliding clutch disposed coaxially with said motor for connecting or disconnecting said member with respect to the terminal element of said transmission means.

23. In a mining machine having a feed 30 operating member rotatable on a horizontal longitudinally extending axis, a flexible feeding element cooperating therewith, and cooperating guiding mechanism for said flexible element including a plurality of series of 35 guiding members disposed on vertical longitudinally spaced parallel axes, at each side of the axis of said feed operating member, said series of guiding members each being vertically disposed from one another and said 40 guiding members being arranged into two groups respectively at opposite sides of a plane to which the axis of the feed operating member is perpendicular and adapted to selectively guide said flexible element in opposite 45 directions and from opposite sides of the machine.

24. In a mining machine, a feed operating member rotatable on a horizontally disposed longitudinally extending axis, a flexible feeding element cooperating therewith, and cooperating guiding mechanism for said flexible element including a plurality of guiding 55 members disposed on longitudinally spaced parallel vertical axes on each side of and in horizontal planes above and below the axis of said feed operating member, said guiding members being adapted to selectively guide said flexible element in opposite directions and from opposite sides of the machine and 60 said guiding members being arranged into 65

two groups respectively at opposite sides of a plane to which the axis of the feed operating member is perpendicular.

25. In a mining machine, a frame having a feed operating member thereon rotatable on a horizontal longitudinally extending axis, a flexible feeding element cooperating therewith, and cooperating guiding mechanism for said flexible element including a plurality of series of coaxial guiding members 70 disposed on longitudinally spaced parallel vertical axes on each side of the axis of said feed operating member, said guiding members being positioned to permit the flexible feeding element to be led to each of the same 75 in a straight line from the feed operating member and being adapted to selectively guide said flexible element in opposite directions and from opposite sides of the machine.

26. In a mining machine, a frame having a feed operating member thereon rotatable on a horizontal longitudinally extending axis, a flexible feeding element cooperating therewith, and cooperating guiding mechanism for said flexible element including a plurality of series of coaxial guiding members 80 disposed on longitudinally spaced parallel vertical axes on each side of and in horizontal planes above and below the axis of said feed operating member, said guiding members being positioned to permit the flexible feeding element to be led to each of the same 85 in a straight line from the feed operating member and being adapted to selectively guide said flexible element in opposite directions and from opposite sides of the machine.

27. In a mining machine, a feed operating member rotatable on a horizontal axis, a flexible feeding element cooperating therewith, and a guiding mechanism for said feeding element including guiding members disposed on longitudinally spaced parallel vertical axes and above and below the axis of said feed operating member at each side of the machine, said guiding members being 90 positioned to permit the flexible feeding element to be led to each of the same in a straight line from the feed operating member and being adapted to selectively guide said flexible element in opposite directions and from opposite sides of the machine.

28. In a mining machine, a frame having a feed operating member thereon rotatable on a horizontal longitudinally extending axis, a flexible feeding element cooperating therewith, and cooperating guiding mechanism for said flexible element including on each side of the feed operating member a series of coaxial guiding members spaced in different horizontal planes and disposed on vertical axes spaced longitudinally of the machine in a vertical plane parallel to the axis of the feed operating member, said guiding members being adapted to selectively guide said flexible element in opposite directions and from opposite sides of the machine.

tions and from opposite sides of the machine.

29. In a mining apparatus, a mining machine having a feed operating member adapted to cooperate with flexible feeding means and feed transmission means including a driven element, a truck driving element, and means for selectively connecting said driven element in driving relation directly with said feed operating member or said truck driving element precluding simultaneous drive of said feed operating member and truck driving element.

30. In a mining apparatus, a mining machine having a feed operating member adapted to cooperate with flexible feeding means and feed transmission means including a driven gear, a truck driving gear, and means including a sliding clutch gear for selectively connecting said driven gear in driving relation with said feed operating member or said truck driving gear.

31. In a mining machine, feeding means including a flexible feeding member, a feed operating member rotatable upon a horizontal axis disposed longitudinally of the machine frame, and rotatable guide members for said flexible member at one side of said feed operating member, said guide members being rotatable on vertical axes spaced longitudinally of the machine in a vertical plane parallel to the axis of the feed operating member and so disposed in different horizontal planes that said flexible member may be selectively extended directly from opposite points on said feed operating member to different guide members.

32. In a mining machine, feeding means including a flexible feeding member, a feed operating member associated therewith rotatable on a horizontal axis extending longitudinally of the machine frame, and rotatable guiding means for said flexible feeding member rotatable on vertical axes spaced longitudinally of the machine and in different horizontal planes whereby said flexible feeding member may be extended to any of said guiding means without intermediate contact with any other and longitudinally in said different planes selectively in either direction relative to said machine.

33. In a mining machine having a feed operating member rotatable on a horizontal axis, and a flexible feeding element cooperating therewith, and cooperating guiding mechanism for said flexible element including a plurality of series of guide members disposed on parallel vertical axes spaced equally from the axis of said feed operating member at each side thereof, said series of guiding members each being vertically disposed from one another and adapted to selectively guide said flexible element in opposite directions and from opposite sides of the machine.

34. In a mining machine, a feed operating

member rotatable on a horizontal axis, and a flexible feeding element cooperating therewith, and cooperating guiding mechanism for said flexible element including a plurality of guiding members disposed on parallel vertical axes spaced equally from the axis of said feed operating member at each side thereof and in horizontal planes above and below the axis of said feed operating member, said guiding members being adapted to selectively guide said flexible element in opposite directions and from opposite sides of the machine.

35. In a mining machine, a frame having a feed operating member thereon rotatable on a horizontal axis, and a flexible feeding element cooperating therewith, and cooperating guiding mechanism for said flexible element including a plurality of series of coaxial guiding members disposed on parallel vertical axes spaced equally from the axis of said feed operating member at each side thereof, said guiding members being adapted to selectively guide said flexible element in opposite directions and from opposite sides of the machine.

36. In a mining machine, a frame having a feed operating member thereon rotatable on a horizontal axis, and a flexible feeding element cooperating therewith, and cooperating guiding mechanism for said feeding element including a plurality of series of coaxial guiding members disposed on parallel vertical axes spaced equally from the axis of said feed operating member at each side thereof and in horizontal planes above and below the axis of said feed operating member, said guiding members being adapted to selectively guide said flexible element in opposite directions from opposite sides of the machine.

37. In a mining machine, a motor having a horizontal armature shaft extending longitudinally of the machine, and feeding mechanism driven by said motor including a feed operating member adapted to cooperate with flexible feeding means and arranged coaxially with said armature shaft, and plural predetermined speed transmission means between said shaft and feed operating member for effecting rotation of the latter at fast and slow speeds in the same direction while said shaft rotates continuously in the same direction.

38. In a mining machine, a motor having a horizontal armature shaft extending longitudinally of the machine, and feeding mechanism driven by said motor including a feed operating member adapted to cooperate directly with flexible feeding means and rotatable on an axis extending longitudinally of the machine, and plural speed transmission means between said shaft and said feed operating member for effecting rotation of the latter at fast and slow speeds in the same

direction while said shaft rotates continuously in the same direction including a fast speed gear train and a slow speed gear train having a gear of each train coaxial and arranged coaxially with said armature shaft.

39. In a mining machine, a motor having a horizontal armature shaft extending longitudinally of the machine, and feeding mechanism driven by said motor including a feed 10 operating member adapted to cooperate with flexible feeding means and rotatable on an

axis extending longitudinally of the machine, and plural speed transmission means between said shaft and said feed operating member for effecting rotation of the latter at a fast speed and a slow speed in the same direction while said shaft rotates continuously in the same direction including fast and slow speed friction clutches arranged coaxially with said shaft.
